UNITED STATES PATENT OFFICE.

NELLY MARGUERITE ROBERT, OF CLEVELAND, OHIO.

FOLDABLE WARDROBE.

Application filed August 19, 1922. Serial No. 582,865.

This invention relates to improvements in foldable wardrobes and appertains more particularly to cabinets or receptacles for wearing apparel constructed of flexible sheet material and capable of being folded when not in use.

It is the purpose of the present invention to provide a wardrobe of the character referred to in which the articles of wearing apparel within the wardrobe are effectually protected against grime, smoke, moths, dust and dirt, to provide for convenient access to the wardrobe for insertion or removal of articles therefrom, to provide a structure which is sanitary and easily cleaned, to provide a structure which can be folded and secured in the form of a compact bundle convenient to carry or to pack for transportation, to provide simple, easily detached parts by means of which the wardrobe may be made rigid and self-supporting, and to accomplish the above objects by means of a structure which may be made of inexpensive materials which can be cheaply manufactured, but which nevertheless is durable and of pleasing appearance.

Other objects will be apparent from the following description and annexed drawing, which set forth in detail certain means embodying the invention, the disclosed means, however, constituting but one of the various mechanical forms in which the principles of the invention may be employed.

Reference should be had to the accompanying drawings forming a part of this specification, in which Fig. 1 is a perspective view of the wardrobe in operative position with the front flaps open; Fig. 2 is a perspective view showing the top and bottom members of the wardrobe folded and the body portion flat; Fig. 3 is a perspective view showing the wardrobe folded and in a compact bundle, and Fig. 4 is a perspective view of the wardrobe with the supporting posts secured thereto; Fig. 5 is a section on line 5-5 of Fig. 4; Fig. 6 is a horizontal section through the front portion of the wardrobe showing the manner of securing the detachable door flaps; Fig. 7 is a fragmentary perspective view of the top member of the wardrobe; Fig. 8 is a detailed view partially in section showing the sections of a supporting post detached; Fig. 9 is a vertical section through a corner of the wardrobe showing the manner of connecting the supporting post of the bottom member. Fig. 10 is a perspec-

tive view showing additional features of construction; Fig. 11 is a top plan view of the structure shown in Fig. 10.

Referring to the annexed drawings, the wardrobe consists of rigid top and bottom members and a body portion formed by a sheet of flexible material connected along opposite edges to the edges of the rigid top and bottom members. The top and bottom members are identical in construction and consist of two rigid rectangular plates or boards 1 and 2 which abut edge to edge and are secured together by hinges 3 secured to the outer faces of the sections 1 and 2. The hinges 3 permit the sections 1 and 2 to fold inwardly. When the wardrobe is in use it is desirable that the sections 1 and 2 be rigidly secured together against folding movement. For this purpose hooks 4 are pivoted to the section 2 and engage pins 5 secured to the section 1 as shown in Fig. 7. A sheet of flexible material is permanently secured to the side and back edges of the top and bottom members forming side walls 6 and 7 and the rear wall 8 of the wardrobe. The free ends of the sheet of flexible material forming the body of the wardrobe are at the front and form door flaps which are detachably secured across the front of the wardrobe. The flap 9 which forms a continuation of the side wall 6 is permanently secured along the front edge of the bottom member. The upper edge of the flap 9 is detachably secured to the front edge of the top member. For securing the flap 9 to the top member complementary snap fastener members 10 and 11 are secured to the section 2 of the top member adjacent the wall 7 and to the upper corner of the flap 9 respectively. The door flap 12 is a continuation of the side wall 7 and is detachably connected to both the top and bottom members. Snap fastener members 13 and 14 are attached to the sections 1 of the top and bottom members on their front and side edges adjacent the corner at the front edge of the wall 6. Complementary snap fastener members 15 and 16 are secured to the upper and lower corners of the flap 12 and engage with the members 13 and 14 on the top and bottom members. As shown in Fig. 6 the flap 12 extends past the corner of the wardrobe and overlaps the side wall 6 at its free edge. The flaps 9 and 12 overlap across the entire front of the wardrobe and form an effective seal against the entry of dust laden air to the

interior thereof. If desired, one or more pockets, such as 17, may be formed upon the inner side or outside of the walls of the wardrobe, also shelves. To provide convenient means for suspending clothes hangers within the wardrobe, a hanger strip 18 of flexible material, or a piece of flat steel, or a kind of drop bar, is secured along one edge to the underside of the section 1 of the top member. The depending portion of the hanger strip 18 is provided with a number of apertures reinforced by suitable eyelets 19 in which the hooks of the clothes hangers can be inserted. When the wardrobe is folded the hanger strip 18 lies flat against the underside of the section 1 of the top member. The top of the wardrobe is covered by a piece of flexible material 20 which has its side edges extending over the edges of the top member and overlying the upper edges of the side walls. The overhanging edges of the member 20 form an effective seal over the upper free edges of the walls and prevent entry of dust between the edges of the top member and the edges of the walls, especially at the front where the detachable connections are provided for the flaps 9 and 12. The walls of the wardrobe and the cover are preferably formed of waterproof material, such as oil cloth, imitation leather, rubberized fabric, or the like, which do not collect dust and which can be readily washed upon the outside. To provide convenient means for carrying the wardrobe when folded into a bundle, as shown in Fig. 3, handle members 22 and 23 are secured to the top and bottom members. An additional handle member 24 may be secured to the top member to provide means for hanging the wardrobe from a suitable support. Straps 25 are secured to the top member and are adapted to encircle the bundle formed by the folded wardrobe, as shown in Fig. 3, the straps 25 being provided with suitable snap fasteners 26 for securing the straps in encircling position.

To make the wardrobe self-supporting, rigid corner posts may be detachably secured between the top and bottom members. These posts are preferably sectional so that they can be secured within the bundle when the wardrobe is folded. The posts consist of sections 27 and 28 which are detachably secured together in any suitable manner, a screw and socket connection being shown.

The post formed by the sections 27 and 28 is of a length just sufficient to fit between the top and bottom members within the flexible wall of the wardrobe. The ends of the posts are provided with threaded sockets 29 which are adapted to register with apertures formed at the corners of the top and bottom members.

At the bottom of the wardrobe, foot pieces 30 have threaded extensions 31 of reduced diameter which extend through the aper-

tures in the bottom member and are screwed into the sockets 29 of the corner posts rigidly clamping the bottom member between the foot piece 30 and the lower end of the corner post. 70

The top of the wardrobe has ornamental knobs 32 which have threaded extensions 33 of reduced diameter which pass through the apertures at the corners of the top member and are screwed into the sockets 29 at the upper ends of the corner posts. When the corner posts are secured in position as above described, they form with the top and bottom members, a rigid frame work which serves to support the wardrobe on the floor. 75 The corner post can be quickly released by unscrewing the foot pieces 30 and knobs 32, and when so released, can be readily removed from the interior of the wardrobe. 80

In folding the wardrobe the sections of the 85 posts may be secured within the bundle.

In Figs. 10 and 11 is shown a foldable wardrobe similar to that previously described, but which embodies some additional features of construction. The top and bottom members and the side walls are formed in substantially the same manner as wardrobe shown in Fig. 1. The flap 12^a, however, has a strip 35 sewed to its upper edge which has snap fastener members 36 secured thereto in which are adapted to engage complementary snap fastener members upon the top of the top member 1^a along its front edge, forming an effective closure along the upper edge of the flap. Otherwise the door flaps are secured in place exactly as shown in Fig. 1. The cover 20^a differs from the corresponding cover shown in Fig. 1, in that the flaps thereof overhanging the upper edges of the side walls and the front flaps thereof have complementary snap fasteners 37 and 38 by means of which they can be secured together and held against the side walls. 95

A detachable lining 40 of silk or other suitable material may be secured upon the inside of the wardrobe. The lining 40 is secured by detachable snap fasteners 41 to the top and bottom members along their side and rear edges and have flaps 42 and 43 overlying the door flaps 9^a and 12^a to which they are detachably secured along their upper and lower edges by snap fasteners 44. The detachable connections permit the lining 40 to be removed when desired for cleaning or pressing. When used upon a wardrobe to which the corner posts are attached the lining covers the posts and conceals them from view. 115

Having described my invention, I claim:

1. A foldable wardrobe comprising collapsible walls of flexible material, and top and bottom members to which said flexible walls are secured, said top and bottom members each formed of two rigid sections hinged together to fold inwardly, said walls 125 130

being foldable between said top and bottom members when the same are folded inwardly to form therewith a compact bundle.

2. A foldable wardrobe comprising top and bottom members each formed of two rigid rectangular sections arranged edge to edge and hinged on the outside along their abutting edges whereby said top and bottom members are adapted to be folded inwardly, means carried by said sections for locking said sections against folding movement, and collapsible walls of flexible material secured to said top and bottom members, said walls being formed of a single piece of flexible fabric, the free edge portions of which overlap across the front of the wardrobe and are detachably fastened to the top and bottom members.

3. A foldable wardrobe comprising walls of flexible material, top and bottom members to which said walls are secured, said top and bottom members each being formed of rigid sections hinged together to fold inwardly, said walls being foldable between said top and bottom members when the same are folded inwardly to form therewith a compact bundle, and handles carried by said top and bottom members.

4. A foldable wardrobe, comprising top and bottom members each formed of rigid rectangular sections arranged edge to edge and hinged to fold inwardly, walls of flexible material secured to the edges of said top and bottom members, said walls being foldable between said top and bottom members when the same are folded inwardly to form therewith a compact bundle, straps secured to the top member and adapted to encircle the bundle, and handles carried by said top and bottom members.

5. A foldable wardrobe, comprising a rigid top member, walls of flexible material secured to said top member, said walls be-

ing foldable, and a hanger receiving member consisting of a strip of flexible material secured along one edge to the under face of the top member and provided with a row of hook receiving openings, said hanger member being adapted to lie flat against the top member when the wardrobe is folded.

6. A foldable wardrobe comprising rigid top and bottom members having apertures adjacent the corners thereof, walls of flexible material secured to said top and bottom members, rigid corner posts the ends of which abut the inner faces of said top and bottom members, said posts having threaded sockets in the ends thereof adapted to register with the apertures in said top and bottom members, foot pieces having threaded extensions of reduced diameter passing through the apertures in the bottom member and engaging in the threaded sockets in the lower ends of the posts, and knobs having threaded extensions passing through the apertures in the top member and engaging in the threaded sockets in the upper ends of the posts.

7. A foldable wardrobe comprising rigid top and bottom members, side and back walls of flexible material permanently secured to said top and bottom members, a front wall formed by flaps forming continuations of opposite side walls overlapping across the front of the wardrobe and detachably secured to the top and bottom members, and a detachable inner lining connected by detachable fasteners to the top and bottom members along the side and rear edges thereof, said lining having flaps overlying the door flaps and attached thereto by detachable fasteners.

In testimony whereof, I hereunto affix my signature.

NELLY MARGUERITE ROBERT.
